CLAIM

The ornamental design for a wearable cardioverter defibrillator connector, as shown and described.

DESCRIPTION

FIG. 1 is a first perspective view of a wearable cardioverter defibrillator (“WCD”) connector, showing aspects of the present design;

FIG. 2 is a second perspective view of the WCD connector of FIG. 1;

FIG. 3 is a third perspective view of the WCD connector of FIG. 1;

FIG. 4 is a fourth perspective view of the WCD connector of FIG. 1;

FIG. 5 is a front view of the WCD connector of FIG. 1;

FIG. 6 is a rear view of the WCD connector of FIG. 1;

FIG. 7 is a top view of the WCD connector of FIG. 1;

FIG. 8 is a bottom view of the WCD connector of FIG. 1;

FIG. 9 is a right view of the WCD connector of FIG. 1;

FIG. 10 is a left view of the WCD connector of FIG. 1; and,

FIG. 11 is a partial cross-section view of the WCD connector of FIG. 1 along line 11-11 of FIG. 5.

The broken lines depict portions of the wearable cardioverter defibrillator connector that form no part of the claimed design; the broken lines form no part of the claimed design.
